Patented Sept. 27, 1921.

UNITED STATES PATENT OFFICE.

FREDERICK E. GERSTENBERGER, OF SOUTH EUCLID, OHIO.

BLOWTORCH.

1,391,774.

Specification of Letters Patent. Patented Sept. 27, 1921.

Application filed June 16, 1919. Serial No. 304,492.

To all whom it may concern:

Be it known that I, FREDERICK E. GERSTENBERGER, a citizen of the United States, and resident of South Euclid, in the county of 5 Cuyahoga and State of Ohio, have invented certain new and useful Improvements in Blowtorches, of which I hereby declare the following to be a full, clear, and exact description, such as will enable others skilled 10 in the art to which it appertains to make and use the same.

The objects of the invention are to provide an improved form of blow pipe, so constructed that a gas of superior quality can be 15 produced therein, which absorbs a maximum amount of oxygen and by increasing the degree of temperature and adding to the intensity of the flame produces more heat units, with a given amount of distillate or 20 other liquid fuel. For this reason, the burner is more economical in its use of fuel.

The super-heating of the fuel vapor and pre-heating of the air also places the carbon content in the fuel in condition to absorb 25 oxygen readily from the atmosphere and hence a high degree of temperature is obtained with a less amount of fuel than in ordinary blow pipe construction.

The construction also permits the flame to 30 be made luminous or non-luminous by controlling the supply of air to the burner.

An expanding chamber is provided mounted upon a super-heating chamber, containing hydrogen evolving ingredients which 35 tends to break up the molecules in the fuel and to saturate the vapor with highly inflammable agents and increase its combustible properties.

The invention includes filtering means in 40 the delivery pipe for collecting all foreign substances or impurities that might clog the burner. It includes the use of two valves, one for controlling the fuel supply to the blow torch or pipe, and a separate valve for 45 controlling the size of the burner jet orifice.

It includes an air pressure pump, which may be attached to the filling cap which is inserted in the dished bottom of the receptacle which forms a funnel for filling the 50 receptacle or the pump may be inserted laterally in the side wall of the receptacle and will then form a handle for the instrument.

The invention is hereinafter more fully described shown in the accompanying drawings and specifically pointed out in the 55 claims.

In the drawings, Figure 1 is a vertical longitudinal section of the preferred form of the device; Fig. 2 is a plan of the same reduced in size; Fig. 3 is a side elevation showing a laterally introduced air-pump which may be used as a handle for the device; Fig. 4 is an enlarged section of the burner valve; Fig. 5 is a transverse section of the vaporizing and superheating chamber employed in 60 the device; Fig. 6 is an enlarged longitudinal section showing the locking device for the pump plunger and passage therethrough.

In these drawings A, represents the receptacle which is preferably polygonal in cross 65 section, for the reason that the walls are made more rigid and the appearance is improved thereby, and it is preferably made more than twice as tall as wide to adapt it for storing in a craftsman's tool kit, and 70 also to adapt it for use with one hand in plumbing and electric work in both vertical and horizontal positions.

B is the filling opening into which a sleeve 75 C, is inserted to which the pump barrel D is attached, thus closing the filling opening. E is the piston and F is a hollow piston rod 80 through which air enters the pump. G is a reed valve over the opening H in a partition I in the pump and J is a second cap 85 which incloses the working valve G and closes the opening in the end of the pump barrel.

This cap is provided with an outlet opening H'.

A second valve is formed by the piston 90 itself when the device is not in use to prevent the escape of fuel or gas. This is formed by the projection S upon the partition I which enters the recess S' in the piston head.

The passage S² in a projection S is closed when the projection enters this recess.

The parts are screw threaded to permit of locking the plunger to the partition to prevent the plunger from falling when the device is not in use.

The air inlet passage through the piston rod can be most conveniently closed by the thumb to prevent the escape of air as shown 105 in Fig. 1.

A packing ring or rings of fiber for the piston are shown at L. M is the vertical outlet passage which is controlled by means of a valve N.

Above the valve is shown the annular vaporizing, expanding and superheating cham-

ber O, and a supply pipe P, leading from the highest level thereof to the burner nozzle Q. In the lower portion of the annular chamber O is shown a collection of elements 5 R, such as aluminum fragments or alloys.

The upper part of this chamber is unobstructed and acts as a vaporizing, expanding and superheating chamber for the fuel oil as it rises from the lower level. At the 10 highest level the outlet or fuel supply pipe extends downwardly and communicates with the burner orifice which discharges axially and through the center of the combined superheating and expanding chamber. The 15 space inclosed by the walls of this chamber can be designated the retort passage or zone, through which the flame is projected, and in which the rate of speed of passage of the flame is controlled by means of the adjustable perforated baffle plate U. The baffle plate U has its periphery threaded to engage the interiorly threaded opening of the expanding and superheating chamber O and the said baffle which is adapted to be rotated 20 to adjust it inwardly and outwardly with reference to the burner nozzle Q is provided with a central opening. Mounted on the supply pipe P is a revoluble plate P' which is adapted to project upwardly as illustrated in full lines in Fig. 1 of the drawings and which is also adapted to be swung downwardly in front of the opening of the expanding and superheating chamber O, as 25 illustrated in dotted lines in Fig. 1. The 30 revoluble plate P serves to control the amount of atmospheric air supplied to the flame. By means of this baffle plate, a multiple number of changes can be made in the size of the flame and in the intensity of its 35 heat units, which it produces, in cooperation with the action of the burner valve at Q.

In the gas supply passage leading to the burner orifice, filtering material is provided at W such a wire gauze made from copper 45 which prevents the burner from being clogged with foreign matter.

The burner orifice is controlled by means of a needle valve of a peculiar shape by means of which the jet produced, will either 50 be expanded into a conical form or contracted to a straight line.

The handle T is so placed as to balance the load and to make it convenient for the operator to handle. This position is shown upon 55 the top of the receptacle as near as possible to the center of gravity and relieves the strain upon the wrist of the operator heretofore most painful to bear.

At Z is shown a drip pan for lighting.

60 At X is shown a fusible plug, in the outlet pipe which fuses at a low temperature and prevents an explosion by gradually liberating the gasses when the fuse is burned out.

In Fig. 4 the construction of the valve 65 controlling the burner orifice is shown. A

needle valve Q controls a fine outlet opening or perforation Q'. A ball Q² upon the valve is seated at Q³ over the outlet opening when the valve is closed, the effect of this enlargement of the valve being to cause the projected spray to contract at the opening and to change the shape of the spray from a straight line to an open cone.

This causes it to commingle more freely 75 with the atmosphere and to make the volume of flame controllable without reducing the operating pressure. The ball enlargement also gives a more substantial support to the needle valve.

By means of the two valves N and Q the operator is enabled to produce a homogeneous mixture at all varying atmospheric conditions of pressure and temperature.

Having described the invention, what I claim as new and desire to secure by Letters 85 Patent is:

1. In a blow pipe, an annular chamber, a supply pipe for fuel oil under pressure, leading into the lower part of said chamber, a supply pipe for fuel gas leading from the 90 upper part of said chamber, a burner nozzle in said fuel gas supply pipe arranged to discharge axially into said chamber, and supplying heat thereto for superheating, expanding and vaporizing said fuel oil 95 therein, a baffle plate in the central opening in said annular chamber and adjustable longitudinally thereof.

2. In a blow pipe, an annular chamber, a supply pipe for fuel oil under pressure, 100 leading into the lower part of said chamber, a supply pipe for fuel gas leading from the upper part of said chamber, a burner nozzle in said fuel gas supply pipe arranged to discharge axially into said chamber, and 105 supplying heat thereto for superheating, expanding and vaporizing said fuel therein, a baffle plate in the central opening in said annular chamber and adjustable longitudinally thereof.

3. In a blow pipe an annular chamber, a fuel supply pipe leading to the bottom of said chamber, a gas outlet pipe leading from the top of said chamber, a burner nozzle in said vapor outlet pipe, said nozzle 115 discharging into the opening in said chamber, a needle valve for said burner nozzle, said valve provided with an enlargement and said nozzle provided with a complementary seat adapted to project the vapor 120 in the form of a cone into the central opening in said chamber, said valve adjustable to vary the form of the vapor jet.

4. In a blow pipe in combination, a receptacle, a pump barrel and a piston and 125 piston rod therein, said piston and rod provided with a continuous longitudinal opening, a transverse partition extending entirely across said barrel in spaced relation with the ends of the same, a projection on 130

said partition, said partition and projection provided with a continuous opening, said piston provided with a recess, adapted to receive said projection, said piston closing

5 said opening when said projection is inserted in said opening and an exterior valve for said opening.

5. In a blow pipe in combination, a receptacle, a pump barrel and a piston and piston rod therein, said piston and rod provided with a continuous longitudinal opening, a transverse partition extending entirely across said barrel, a projection on said partition, said partition and projection provided with a continuous opening, said piston provided with a recess, adapted to receive said projection, said piston closing said opening when said projection is inserted in said recess and an exterior valve

for said opening, and an exterior cap for 20 said barrel said cap provided with an opening for air outlet and confining the partition in position.

6. In a blow pipe, an annular superheating, vaporizing and expanding chamber, a 25 supply pipe for fuel oil thereto, an outlet pipe leading from the top of said chamber, a burner nozzle discharging into the central opening in said chamber, and a revoluble plate adapted to be interposed between said nozzle and said central opening.

In testimony whereof I hereunto set my hand this 14th day of April, 1919.

FREDERICK E. GERSTENBERGER.
